UNITED STATES PATENT OFFICE.

GUSTAV A. BARTH, OF ST. LOUIS, MISSOURI, ASSIGNEE TO PIERRE CHOUTEAU, OF SAME PLACE.

CARRIAGE FOR DIRECT-ACTING ROCK-DRILLS.

SPECIFICATION forming part of Letters Patent No. 397,623, dated February 12, 1889.

Application filed October 18, 1888. Serial No. 288,501. (No model.)

To all whom it may concern:

Be it known that I, GUSTAV A. BARTH, a citizen of the United States, residing at the city of St. Louis, State of Missouri, have invented a certain new and useful Improvement in Carriages for Direct-Acting Steam or Pneumatic Rock-Drills used for Mining Purposes, of which the following is a full, clear, and exact description.

- 10 My invention relates to an improved carriage for supporting a direct-acting steam or pneumatic engine while in operation as a machine for chipping and mining purposes, and has for its object to prevent the recoil of the machine when the tool strikes the material to be dislodged, and thereby remove the strain hitherto thrown on the operator when the machine is mounted on wheels in the usual manner.
- 15 It consists in a horizontally-arranged block or cradle provided with bearings, in and between which is mounted the machine on pivots or trunnions, the cradle being swiveled centrally to a bed-plate provided on its under side with rollers, whereby the entire apparatus is supported and enabled to be moved along a platform or planking to which the bed-plate is securely held at any point by a hooked screw-bolt, (or bolts,) which passes through
- 20 the bed-plate, and is provided with a nut and handle, so that on turning the nut in one direction the screw-bolt is raised, and its hooked portion catching against the under side of the plank securely clamps the bed-plate thereto, and thereby prevents the machine from recoil when the blow of the tool is given.
- 25 On the accompanying drawings, Figure 1 represents a side elevation of my improved carriage with a mining-engine, broken away, mounted thereon; Figs. 2 and 3, a rear end view and plan thereof, respectively; and Fig. 4, a sectional view on an enlarged scale on line 11 in Fig. 1, like letters of reference denoting like parts in all the figures.

- 30 *a* represents an elliptical or other suitably-shaped block or cradle having a circular base, which is arranged horizontally and formed with two opposite upwardly-projecting sides, in each of which is a bearing, *b*, the two bearings *b* being opposite to each other in the

same plane, and at a suitable distance apart for receiving the pivots or trunnions *c* of the mining-machine *d*, which is mounted between and at right angles longitudinally to the bearings *b*, and projects at each end beyond the 55 cradle *a*.

The front end of the machine *d*, as seen broken away to the left of Figs. 1 and 3, carries the chipping or other mining tool with its appendages in the usual manner, while to the 60 rear end of the machine is attached one or more handles, *e*, for directing the apparatus to its work.

The cradle *a* is supported on and swiveled centrally to a bed-plate, *f*, by a circular stud 65 or projection, *g*, which is formed on or attached to the under side of the base of the cradle *a*, and fitted into a corresponding hole in the bed-plate *f*. To the lower end of the stud or projection *g* is secured a head or collar-plate, *h*, 70 which bears against the bottom of a recess formed therefor in the under side of the bed-plate *f*, so that the cradle *a*, while capable of rotation on the bed-plate *f*, is confined thereto vertically.

At suitable locations in the under side of the bed-plate *f*, and transversely therewith, are formed grooves *i*, having semicircular beds for receiving cylindrical rollers *j*, which project circumferentially slightly beyond the under side of the bed-plate *f* and bear thereat upon a platform or planking, *k*, between which and the bed-plate *f* a space or clearance is thereby left, so that when the apparatus is moved along the planking *k* frictional contact between the latter and the bed-plate *f* is avoided, and the entire weight of the apparatus carried by the rollers *j*, rotating in the grooves *i*.

Formed vertically through the bed-plate *f* at 90 each side thereof, (or on one side only if found preferable,) immediately beyond the edge of the plank *k*, is a square hole, *l*, through which passes a bolt, *m*, having at its upper end a screw-thread which projects partly above the 95 bed-plate *f*, and at its lower end a hook or catch, *n*, which passes beneath and is normally out of contact with the planking *k*.

On the upper screwed portion of the bolt *m* is fitted a nut, *o*, having a lever-handle, *p*, 100

and bearing at its under side against the upper surface of the bed-plate *f* adjacent to the hole *l*.

The machine being mounted on its carriage, 5 as above described, and supported therewith by the rollers *j* on the planking *k*, the entire apparatus is moved along the plank *k* by the handle *e* of the machine *d* until the latter is in the proper position for striking the material. The operator then throws over the lever (or levers) *p* of the nut *o* by his foot toward the front end of the machine or into the position shown by dotted lines in Fig. 3, which causes the nut *o* to be partially rotated against 10 the upper surface of the bed-plate *f* and around the screwed portion of the bolt *m*, which is thereby raised sufficiently to close its hook or catch *n* tightly against the under side of the planking *k*, and so clamp the latter and the bed-plate *f* together, in which position the carriage is immovable endwise and the recoil of the machine transmitted to the planking *k* in lieu of to the operator, as heretofore.

15 The bolt *m* is prevented from turning with the nut *o* by a square collar, *q*, which slides vertically in the hole *l*, or by any other suitable means.

I claim as my invention—

20 1. The combination of a bed-plate having rollers *j* and supported thereby on planking

k, screw-bolt (or bolts) *m*, having hook *n*, and nut *o*, means for rotating said nut, and a block or cradle, *a*, having bearings *b*, with a direct-acting steam or pneumatic engine provided with pivots or trunnions, substantially as shown, and for the purpose described. 35

2. The combination of a bed-plate having rollers *j* and supported thereby on planking *k*, screw-bolt (or bolts) *m*, having hook *n*, collar *q*, and nut *o*, means for rotating said nut, and a block or cradle, *a*, having bearings *b*, with a direct-acting steam or pneumatic engine, provided with pivots or trunnions, substantially as shown, and for the purpose de- 40 scribed. 45

3. The combination of a bed-plate having rollers *j* and supported thereby on planking *k*, screw-bolt (or bolts) *m*, having hook *n*, collar *q*, nut *o*, and lever *p*, and a block or cradle 50 *a*, having bearings *b*, with a direct-acting steam or pneumatic engine provided with pivots or trunnions, substantially as shown, and for the purpose described. 55

In testimony whereof I affix my signature in presence of two witnesses this 13th day of October, 1888.

GUSTAV A. BARTH.
